UNITED STATES PATENT OFFICE.

GEORGE M. TEPPER, OF NEW YORK, N. Y., ASSIGNOR TO NATIONAL METAL SPINNING & STAMPING COMPANY, OF NEW YORK, N. Y., A CORPORATION OF NEW YORK.

DESIGN FOR A SOCKET-COVER FOR LIGHTING-FIXTURES.

47,973.

Specification for Design.

Patented Oct. 12, 1915.

Application filed May 24, 1915. Serial No. 30,231. Term of patent 7 years.

To all whom it may concern:

Be it known that I, GEORGE M. TEPPER, a citizen of the United States, residing at New York city, in the county and State of New York, have invented a new, original, and ornamental Design for a Socket-Cover for Lighting-Fixtures, of which the following is a specification, reference being had to the accompanying drawing, forming part thereof.

The figure is a perspective view of a

socket cover for lighting fixtures showing my new design.

I claim:

The ornamental design for a socket cover for lighting fixtures, as shown.

GEORGE M. TEPPER.
